ANTISKID ATTACHMENT FOR SHOES

Carlo Gabriele, Youngstown, Ohio

Application July 19, 1935, Serial No. 32,282

3 Claims. (Cl. 36—59)

This invention relates to boots and shoes and more particularly to an ice creeper or anti-skid device especially designed for attachment to overshoes.

5 The object of the invention is to provide a shoe or overshoe having cleats secured to the tread surface thereof and so disposed with reference thereto as to permit flexing of the shoe in the act of walking and at the same time effectually prevent slipping or falling of the wearer when walking on ice, snow or other slippery surfaces.

A further object of the invention is to provide an anti-skid device or cleat of simple and durable construction which may be quickly attached to 15 the sole of a shoe or overshoe and worn without discomfort to the wearer.

A further object is to provide an anti-skid device comprising sole and heel sections or cleats each including a base portion conforming to the 20 shape of the tread surface of the shoe and provided with depending spurs constituting a traction surface for engagement with the ground.

A still further object is generally to improve this class of devices so as to increase their utility, 25 durability and efficiency.

In the accompanying drawing forming a part of this specification and in which similar numerals of reference indicate corresponding parts in all the figures of the drawing:

30 Figure 1 is a side elevation, partly in section, of an overshoe provided with an anti-skid device constructed in accordance with the present invention.

Figure 2 is a bottom plan view.

35 Figure 3 is a perspective view of the heel cleat detached.

Figure 4 is a transverse sectional view taken on the line 4—4 of Figure 2.

Figure 5 is a transverse sectional view taken 40 on the line 5—5 of Figure 4.

The improved anti-skid device while capable of attachment to all kinds of shoes, such as men's, ladies' and children's shoes, is principally designed for use in connection with overshoes 45 and by way of illustration is shown in connection with an overshoe of conventional construction in which 5 designates the upper, 6 the heel, and 7 the outer sole.

The anti-skid device is preferably formed of 50 three cleats or sections, a toe cleat 8, heel cleat 9, and intermediate sole cleat 10. The toe cleat 8 is preferably stamped or otherwise formed from sheet metal and comprises three relatively short forward arms 11 which project in the direction

of the toe portion of the shoe and two relatively long rear arms 12 and 12' of unequal length, the end of one of which is disposed adjacent one marginal edge of the sole 7 and the end of the other arm 12 being disposed near the other marginal edge of the shoe, as best shown in Figure 2 of the drawing. The metal constituting the toe cleat is bent or struck up to form terminal spurs 13, preferably concavo-convex in cross section, as indicated at 14, and terminating in impaling 10 points 15 adapted to engage a slippery surface such as ice or snow and prevent slipping of the wearer in the act of walking thereon. Adjacent each spur 13 is an opening 16 through which extends a rivet or similar fastening device 17 15 for engagement with the sole 7 so as to prevent accidental displacement of the cleat. It will thus be seen that the arms 11 conform to the shape of the toe portion of the shoe, while the arms 12 and 12' extend transversely of the sole 20 7 so that the terminal spurs on said arms entirely surround the toe portion of the shoe and provide a roughened surface for engagement with the ground.

The central or intermediate cleat 10 is preferably substantially triangular in shape and the metal at the opposite ends of the forward or wide portion of the cleat is bent or struck up to provide spurs similar in construction to the spurs 13, it being preferred, however, to omit the spur at 30 the rear side of the intermediate cleat, as best shown in Figure 2 of the drawing. The intermediate cleat 10 is secured to the sole of the overshoe by rivets similar in construction to the rivets 17 which rivets pass through openings 19 formed 35 in the cleat and one of these rivets is preferably disposed at the apex of the rear portion of the cleat, as indicated at 20, in lieu of positioning a spur at that point.

The heel cleat 9 preferably consists of intersecting bars 21 having terminal depending spurs 22 similar in construction to the spurs 13, said heel cleat being secured to the heel 6 of the shoe by the rivets previously referred to.

In positioning the anti-skid device on an overshoe or other article of footwear, the toe cleat is arranged adjacent the toe of the shoe with the long arm 12 extending outwardly across the tread surface of the sole 7 and the short arm 12' extending inwardly, as best shown in Figure 2 of the drawing. The intermediate cleat 10 is then positioned on the shoe sole 7 with the apex of the cleat extending in the direction of the instep and spaced a sufficient distance from the toe cleat to 55

permit free flexing of the sole of the shoe in the act of walking. The heel cleat 9 is riveted to the heel 6 with the short ends of the bars 21 extending in the direction of the rear end of the heel and the long ends of the bars 21 extending in the direction of the corners of the breast of the heel.

While the device is principally designed for attachment to overshoes, it will be understood that 10 said device may be secured directly to the tread surface of a boot, shoe, or other article of footwear and may be applied to any style of shoe, such as men's, ladies', or children's shoes without departing from the spirit of the invention.

15 Having thus described the invention, what is claimed as new is:

1. The combination with a shoe including a heel and sole, of an anti-skid device comprising a toe cleat having spaced front arms of substantially 20 the same length radiating forwardly and diverg-

ing rear arms of different lengths, all of said arms being provided with depending spurs.

2. The combination with a shoe including a heel and sole, of an anti-skid device comprising a toe cleat secured to the sole of the shoe and having relatively short front arms radiating forwardly and diverging rear arms of different lengths, the material forming the cleat being bent at the ends of the several arms to form depending spurs substantially concavo-convex in 5 cross section.

3. A toe cleat for shoes stamped from a single sheet of metal to form relatively short front arms of substantially the same length radiating forwardly and diverging rearwardly extending long 15 arms of different lengths, the metal at the ends of the several arms being bent to form depending spurs substantially concavo-convex in cross section.

CARLO GABRIELE. 20
